[57] CLAIM

The ornamental design for a low cost hardware container, as shown and described.

DESCRIPTION

FIG. 1 is a perspective view taken from the top, front and right side of a low cost hardware container, showing my new design;

FIG. 2 is a bottom view thereof;

FIG. 3 is a rear view thereof;

FIG. 4 is a right side elevation view thereof, the left side elevation view being a mirror image;

FIG. 5 is a cross sectional view taken on line 5—5 of FIG. 1 showing the lifting knob in the resting position; and,

FIG. 6 is a cross sectional view taken on line 6—6 of FIG. 1 showing the lifting knob extended.
